RECLOSING CIRCUIT BREAKER

Joseph S. Thompson and Charles E. Ray, San Francisco, Calif., assignors to Pacific Electric Manufacturing Corporation, San Francisco, Calif., a corporation of California

Application July 22, 1940, Serial No. 346,816

18 Claims. (Cl. 200—89)

Our present invention relates to circuit breakers, and more particularly to circuit breakers of the so-called reclosing type which are adapted to open and automatically reclose an electrical circuit upon the occurrence of an overload or fault thereupon.

An object of the invention is to provide a reclosing circuit breaker for electric power systems that will give overload protection and predetermined automatic reclosures of the circuit in a reliable and efficient manner.

Another object of the invention is to provide an automatic reclosing circuit breaker in which the reclosing operations thereof are carried out by mechanical means independently of current conditions upon the power line connected therethrough.

Another object of the invention is to provide an automatic reclosing circuit breaker with time delay means which, upon the occurrence of a sustained overload or fault upon the line, will serve to delay the second reclosing operation for a period of time greater than that of the first reclosing operation.

Another object of the invention is to provide an operating mechanism for an automatic reclosing circuit breaker which will instantaneously reclose the circuit breaker upon the initial occurrence of a fault and provide for subsequent reclosings at predetermined intervals, should the fault continue after the first opening of the circuit breaker.

Another object of the invention is to provide an automatic circuit interrupting and reclosing circuit breaker of the spring operated type which can be manually controlled in a simple and convenient manner.

Another object of the invention is to provide a spring operating mechanism for an automatic reclosing circuit breaker in which novel means is provided to maintain the spring in a predetermined wound condition.

Another object of the invention is to provide automatic time controlled tripping and reclosing means for an automatic circuit breaker in which the opening and reclosing operations are delayed for predetermined intervals upon the occurrence of a fault upon the power line.

Another object of the invention is to provide a timing mechanism for controlling a spring operated reclosing circuit breaker which will be rendered inoperative when the circuit breaker operating spring approaches a predetermined unwound condition.

Other objects and advantages of the inven-

tion will be in part evident to those skilled in the art and in part pointed out hereinafter in connection with the accompanying drawings, wherein there is shown by way of illustration and not of limitation preferred embodiments of the several features of this invention.

In the drawings:

Figure 1 is a fragmentary view partially in section showing a conventional circuit breaker of the multipole type adapted to be operated by the operating mechanism contemplated by this invention.

Figure 2 is a vertical view with parts in section showing the circuit breaker contacts in their closed circuit position.

Figure 3 is a vertical view taken along line III—III of Figure 1 showing the arrangement of the circuit breaker operated and timing mechanisms.

Figures 4 and 5 are enlarged views showing details respectively of the circuit opening and reclosing latches illustrated in Figure 3 of the drawings.

Figure 6 is a vertical sectional view taken along the center of the circuit breaker operating spring shown in Figure 1 of the drawings.

Figure 7 is an end view of the spring operating mechanism illustrated in Figure 6 with parts broken away to illustrate the construction of a preferred form of spring holding and winding motor.

Figure 8 shows the interior of the reclosing timer mechanism illustrated in Figure 3 of the drawings.

Figure 9 is a fragmentary view taken along line IX—IX of Figure 1 showing the manner in which the reclosing timer mechanism is set in operation upon an opening of the circuit breaker.

Figure 10 is a fragmentary view of the reclosing timer mechanism taken along line X—X of Figure 9 looking in direction of arrows.

Figure 11 is an enlarged fragmentary view of a detail of the timer mechanism.

Figures 12, 13 and 14 are fragmentary views showing details of the timer controlled reclosing latch operating mechanism under different conditions of operation, and

Figure 15 is a plan view of the timer mechanism illustrated in Figure 12.

The apparatus contemplated by the present invention is similar in many respects in its mode of operation to the apparatus disclosed in U. S. Patent No. 2,125,465, issued August 2, 1938, to August C. Schwager and Paul Frehner, entitled

Automatic reclosing circuit breaker, and assigned to the assignee of this invention. In its details of construction, however, this invention is considered an improvement upon the aforesaid disclosure in that it provides a different type of operating means which is particularly suitable for use in connection with circuit breakers of higher voltage and current capacities.

The purpose of the present invention, like that disclosed in the above patent, is to provide a reclosing circuit breaker which is adapted to provide overload protection on a transmission line with automatic reclosures at predetermined intervals and to this end the circuit breaker operating mechanism is so constructed that it will automatically open the circuit upon the occurrence of an overload or fault and immediately thereafter reclose the circuit so that should the fault be cleared, the circuit will be immediately re-established. In the event that the overload or fault is of a continuous nature, the operating mechanism is adapted to again open the circuit and after a predetermined time delay, again reclose the circuit, this operation being repeated through two or more reclosing operations after which, should the overload or fault still exist upon the circuit in which the circuit breaker is connected, the circuit breaker operating mechanism will be rendered ineffective to produce a further reclosing of the circuit breaker.

For the purpose of a detailed description of the invention, there is shown in the drawings a circuit breaker of the three-pole type in which a bridging member is movable with respect to two spaced stationary contacts into a circuit closed or a circuit opened position in the conventional manner well understood in the art.

Reference is now made to Figure 1 of the drawings for a general description of the apparatus as a whole, and later the various novel aspects thereof will be taken up in detail in connection with the remaining figures of the drawings. In this figure of the drawings, the numeral 10 designates a frame that is adapted to be secured upon any suitable support and from which there is suspended a tank 11 that is adapted to enclose the circuit controlling contacts of the circuit breaker and contain a suitable insulating and arc extinguishing liquid 12, such as oil. The frame 10 also supports a cover forming member 13 which is suspended therefrom so as to enclose the circuit breaker controlling and operating mechanisms which are here designated respectively by the numerals 14 and 15. As shown, the controlling mechanism 14 is in the main supported upon a transversely extending panel-like member 16 that is likewise carried by the frame 10, and the operating mechanism 15 is supported upon a suitable bracket 17 which is carried by the panel-like member 16. The frame 10 has a web or partition 18 which serves to separate the controlling mechanism 14 from the circuit controlling elements of the circuit breaker. This partition 18 also serves to support one end of a circuit breaker operating shaft 19 that extends therethrough and is disposed along one side of the circuit breaker contacts. As shown, the shaft 19 has spaced inwardly extending arms 20 which are movable through an arc as the operating shaft 19 is oscillated and at their free ends these inwardly extending arms 20 are connected through a suitable linkage 21 to a longitudinally extending bar 22. Suspended from the bar 22 and guided in a vertical path by guide members 23 there is a suitable insulating support 24 for

each phase of the circuit breaker, upon the lower ends of which contact bridging members 25 are mounted. With this arrangement, when the shaft 19 is oscillated, the insulating supports 24 will move up and down in a vertical direction through the guide members 23 and thus carry the contact bridging members 25 into and out of cooperating relation with the stationary contacts of the circuit breaker. At its projecting end, the shaft 19 has a lever arm 26 that is connected through a pitman 27 to an eccentric crank arm 28 which is adapted to be moved intermittently through successive arcs of 180°. The crank arm 28 is rotated by a shaft 29 that is driven by a small gear 30 that meshes with a larger gear 31 carried by an end plate 32 to which the free end of an energy storing operating spring 33 is connected. At its other end the operating spring 33 is connected to a rotatable end plate 34 which has gear teeth that mesh with an idler gear 35 which in turn meshes with a pinion gear 36 upon the shaft of an energized electric spring winding motor 37. It will be noted that the idler gear 35 has an axial length substantially longer than the gear teeth upon the end plate 34. This is to permit axial movement of the end plate 34 with respect to the idler gear 35 as this end of the operating spring 33 moves in and out when the spring 33 is being wound and/or unwound. At this point it should be stated that the spring winding motor 37 is of novel design in that it is of a non-reversible character, and as a result, in addition to its function of maintaining the operating spring 33 in a predetermined wound condition, it also serves to hold the operating spring 33 in a wound condition without resort to a ratchet or other like device. As a means to provide for a manual winding of the operating spring 33, the bracket 17 is shown as having a supporting plate 38 suspended from the end thereof upon which there is mounted a longitudinally movable stop 39 and a longitudinally movable end plate engaging member 40 that operates upon the ratchet principle to turn the end plate 34 in a spring winding direction when an operating force is applied thereupon by means of a manual lever 41 carried thereby. The nature of this manual spring winding mechanism is to be described in detail hereinafter.

The above briefly describes the manner in which the circuit breaker operating forces exerted by the operating spring 33 are transmitted to the movable contact bridging members 25 when the operating mechanism 15 is set in motion to effect an opening and/or a closing of the circuit breaker contacts. For the purpose of rendering the controlling mechanism 14 responsive to overload or fault conditions upon the circuit to be protected by the circuit breaker, there is provided an overload trip coil 42 which is in series with the contacts of each phase of the circuit breaker. This trip coil 42, as is more clearly shown in Figure 2 of the drawings, is adapted to influence an armature 43 which is connected through an insulated rod 44 to a trip operating shaft 45. Each of the trip coil operated rods 44 is connected eccentrically to the trip shaft 45 with a lost motion connection mechanism 46 which permits any one of the trip coils 42 to operate independently of the others upon the occurrence of an overload or fault on any one of the phases of the circuit breaker. Like the circuit breaker operating shaft 19, the trip shaft 45 extends through the partition 18 of the frame 10 and at its extending end it carries a crank arm

47 to which a toggle collapsing link 48 and a time controlling link 49 are connected.

Upon further reference to Figure 2 of the drawings, it will be noted that the circuit operating shaft 48 is mounted well to one side of the center of the circuit breaker upon bearings 50, and as a result the free ends of the inwardly extending arms 28 carried thereby will move in substantially vertical arcs. Therefore, as a result of the linkage 21 at the ends of the arms 28 and the vertical guide members 23, the bridging contact supporting members 24 will move vertically with a straight line motion. As here illustrated, the contact bridging members 25 are provided with upstanding contacts 51 which are adapted to extend into an arc expulsion chamber 52 that surrounds stationary contacts 53 carried by terminals 54 located within the circuit breaker tank 11 and at the lower ends of suitable insulating bushings 55 that carry exposed terminals (not shown) to which the power circuit conductors are connected. At this point it should be stated that the stationary contact 53, with which the trip coil 42 is associated, is mounted within its expulsion chamber 52 independently of its supporting terminal 54 so that the circuit of the trip coil 42 can be interposed therebetween by conductors 56 and 57, as is well understood. This latter figure of the drawings clearly illustrates the nature of the lost motion connection mechanism 46 through which the trip coil operated rods 44 are connected to the trip operating shaft 45. As here shown, each of the insulated rods 44 is provided with a pin 58 which engages a slot 59 in lever forming members 60 carried by the trip operating shaft 45. With this arrangement, when any one of the rods 44 is pulled down by an associated armature 43, it will impart a partial rotation of the shaft 45 sufficient to set the controlling mechanism 14 in operation independently of the trip coils 42 which are associated with the other poles of the circuit breaker.

Reference is now made to Figure 3 of the drawings for a more detailed description of the controlling mechanism 14 which serves to automatically control the opening and closing operations of the circuit breaker under the influence of the energy storing spring 33. In this figure of the drawings it will be noted that the eccentric crank arm 28, to which the pitman 27 is connected, extends outwardly from a disc 61 that is secured to the end of the shaft 29. In addition to the crank arm 28, this disc 61 also has a radially extending latch engaging abutment 62 that is adapted to be stopped in opposite substantially horizontal positions by toggle controlled latches 63 and 64 which respectively stop the disc 61 with the crank arm 28 in its circuit breaker closed and opened positions. In other words, the latch 63 is arranged so that when operated it will permit the circuit breaker contacts to open, and the latch 64 is arranged so that when it is operated into its disc releasing position, it will permit the spring 33 to reclose the circuit breaker contacts. These latches 63 and 64 will be described in more detail in connection with Figures 4 and 5 of the drawings. Therefore, for the present it will be sufficient to note that the position of the abutment engaging portion of the latch 63 is controlled by toggle forming links 65 and 66 which are connected at their meeting ends to the toggle operating link 48 previously referred to as operatively connected to the crank arm 47 which is carried by the trip shaft 45. As here shown, the link 48 has an elongated slot 71 at its upper end 75

that provides for a limited amount of lost motion between it and the crank arm 47. Unlike the link 48, the time controlling link 49 is attached directly to the end of the crank 47 and at its lower end this link 49 is connected to a lever arm 68 which is adapted to move upwardly with a time controlled movement, the period of which is determined by a suitable escapement 69 that determines the speed of rotation of a shaft 70 upon which the lever arm 68 is mounted. With this arrangement it will be seen that when the crank arm 47 is released after such a toggle tripping action, the links 48 and 49 will fall by gravity and thus reset the toggle links 65 and 66 to position the circuit opening latch 63 in its normal operative position. As a means to provide for a manual operation of the circuit opening latch 63, there is provided a lever arm 71 that is pivotally mounted upon a shaft 72 located substantially centrally upon the supporting panel 16. This lever arm 71 has an outwardly extending pin 73 at its end which is disposed beneath an outwardly extending boss 74 carried by the toggle collapsing link 48. For the purpose of moving the pin 73 upon the lever arm 71 upwardly and into operating engagement with the boss 74, the lever arm 71 has an oppositely extending arm 75 over which the end 76 of a manual operating push and/or pull rod 77 passes. The lever arm 71 also has an upstanding portion 78 that is adapted to engage a stop 79 under the influence of a spring 80. The lever arm 71 is also shown as operatively connected to an armature 81 of an electromagnet 82 by means of a link 83. This latter expedient is to provide for a remote electrical control of the opening latch 63 from a push button control station independently of the automatic trip coil control provided for by the overload trip coils 42 in the power line circuit. It will now be seen that when the toggle collapsing link 48, which serves to control the circuit breaker opening latch 63, is raised by an upward movement of the lever arm 47 through a rotation of the trip coil operated shaft 45 under the influence of an overload or fault on any one of the overload trip coils 42, or by a manual operation of the lever arm 71 by a pulling down upon the push and/or pull rod 77, or by a rotation of the lever arm 71 by means of the armature 81 in response to an energization of the electromagnet 82 in response to a push button control circuit, the toggle links 65 and 66 will be drawn upwardly into their toggle collapsed positions and as a result the opening latch 63 will be moved out of engagement with the abutment 62 upon the plate 61 and as a result the crank arm 28 will be carried around into its opposite or circuit breaker open position where it will be stopped by an engagement of the abutment 62 with the reclosing latch 64, where the circuit breaker contacts will remain in their open circuit position until the reclosing latch 64 is operated, as will now be described.

Like the circuit opening latch 63, the reclosing latch 64 is also moved into and out of operative relation with the abutment 62 upon the disc 61 by toggle links 84 and 85, the latter of which, as is more clearly illustrated in Figure 5 of the drawings, has an outwardly extending end 86 that carries a timer engaging link forming device 87 at its outer end. As here shown, the timer engaging link forming device 87 is biased into a timer engaging position by means of a spring 88 that is carried by a member 89 which is made responsive to the wound condition of the energy

storing spring 83 by means of a slideable member 80, as will be described in detail hereinafter. As here shown, the timer engaging link 87 is biased outwardly into the path of a projecting lug 81 formed upon a sector 82 which is adapted to be moved, as will also be hereinafter pointed out, into a lowered position by means associated with the circuit breaker operating spring 88 upon each opening movement of the circuit breaker, after which the sector 82 will be released and permitted to move upwardly with a time controlled movement and into a toggle link tripping engagement with the link device 87 by an operating means in the form of any suitable escapement type of timing mechanism 83. In order to provide for a manually or a remote push button controlled operation of the reclosing latch 84, there is an independently movable lever arm 84 that is freely pivoted upon a shaft 85 of the reclosing timer mechanism 83 and upon which the sector 82 is secured. This lever arm 84 has an extending end which, like the lug 81 upon the sector 82, is adapted to be moved into engagement with the timer engaging link 87 to collapse the toggle links 84 and 85 when it is moved upwardly. This upward movement of the lever arm 84 is effected through a link 86 which is carried by an additional lever means 87 that is pivotally mounted upon the centrally disposed shaft 72 which likewise supports the lever arm 71. This lever means 87 has an upstanding portion 88 which is held in abutting relation with the stop 79 by means of the spring 80, as is the case with the lever arm 71. Intermediate its free end and the shaft 72, the lever means 87 is provided with an elongated slot 89 which will permit a downward movement of the push and/or pull rod 77 and also engage the projection 78 thereupon so that when the rod 77 is pushed upwardly, the lever means 87 will be moved upwardly with the link 86 and move the toggle tripping lever arm 84 into operating relation with the timer engaging link 87 of the reclosing latch 84. A similar operation of the lever means 87 by remote push button control is also provided for by means of an electromagnet 100 which has an armature 101 that is connected thereto by a connecting link 102. Before proceeding with a detailed description of the construction of the opening and reclosing latches 83 and 84, attention is again directed to the lever arm 71 for the purpose of pointing out that this lever arm 71 also carries a downwardly and rearwardly extending arm 103 which projects through the panel-like support 104 and is connected to a slideable member 105 at the back thereof which is adapted to render the reclosing timer mechanism 83 inoperative in the event of a manual and/or a remote push button controlled opening operation of the circuit breaker. It will also be noted that the trip coil operated shaft 45 is biased into its normal inoperative position by means of a spring 106 which is connected between a wall of the frame 10 and an arm 107 formed upon the crank arm 47.

Reference will now be made to Figures 4 and 5 of the drawings for a detailed description of the opening and reclosing latch mechanisms 83 and 84 which, as stated above, cooperate with the abutment 82 to stop the operating mechanism 15 with the circuit breaker contacts respectively in their closed and opened circuit positions. Except for the difference between the toggle links 84 of the latch 83 and the link 85 of the latch 84, and possibly some slight differences in the dimensions of the several parts, they are identical.

in construction and mode of operation. As illustrated, the moving parts of these latches 83 and 84 are mounted upon a surface plate 107 and move between side walls 108 secured thereupon that have upstanding ears 109 between which the toggle links 84 and 85 are pivotally mounted. In Figure 4, the moving parts of the latch 83 are shown as comprising an abutment forming member 110 having a horizontally extending base 111 that provides a surface opposed to the surface plate 107 between which two spaced anti-friction rollers 112 are positioned so that the abutment forming member 110 can be moved into and out of interfering relation with the abutment 82 upon the disc 81. For the purpose of holding the horizontally extending base 111 of the abutment forming member 110 in cooperating relation with the anti-friction rollers 112, the side walls 108 carry two transversely extending guide rods 113 which are positioned in spaced relation above the ends of the base 111. At its upper end the abutment forming member 110 carries an anti-friction roller 114 which is held in position thereupon by means of an adjustable cage 115 that permits a limited rolling of the roller 114 thereupon, as when the latch 83 is operated to release the disc 81 and permit an opening of the circuit breaker contacts. The abutment forming member 110 with its base 111 are also here shown as biased into latching relation with the abutment 82 upon the disc 81 by means of a compression spring 116. This spring 116 is coiled about a guide rod 117 which is pivotally secured to a downwardly extending arm 118 carried by the link 86. With this arrangement it will be seen that in addition to biasing the abutment forming member 110 in cooperating relation with the abutment 82, the spring 116 will also serve in conjunction with the weight of the link 86 to move the toggle links 84 and 85 into their extended position. As illustrated in Figure 5 of the drawings, the abutment forming member 110 with its horizontally extending base 111 is positioned below the surface plate 107 where it will be held in cooperating relation with the anti-friction rollers 112 by guide rods 113, previously referred to as carried by the side walls 108. In other words, the movable elements of the latch 84 may be referred to as positioned in an upside down position with respect to the corresponding moving elements of the latch 83. In the latch 84 the links 84 and 85 are shown as biased into an extended position by means of a compression spring 119 that is coiled about a guide rod 120 which is pivotally connected to an arm 121 formed upon the link 85. In this arrangement it will be seen that when an upwardly directed pulling force is exerted upon the link forming device 87 carried by the extending end 86 of the toggle link 85, the toggle formed by the links 84 and 85 will be collapsed and as a result the abutment forming member 110 will be moved to the left, as viewed in this figure of the drawings, and thus the anti-friction roller 114 at the end thereof will be carried out of the path of the abutment 82 carried by the disc 81 to permit a reclosing of the circuit breaker contacts. While we have illustrated and here described a specific form of construction for the latches 83 and 84, it is to be understood that these latches may take many other forms, and since their novel construction is not a feature of the present invention, they are to be made the subject matter of a divisional application for patent.

Reference is now made to Figures 6 and 7 of

the drawings for a more detailed description of the construction and mode of operation of the energy storing and circuit breaker operating spring 33 previously referred to in connection with Figure 1 of the drawings. As here shown, the energy storing spring 33 is mounted concentrically with respect to a shaft 122 and between the end plates 32 and 34 to which its corresponding ends are attached. The shaft 122 also carries the larger gear 31 previously referred to as associated in driving relation with the smaller gear 30 carried by the shaft 29 upon which the latch engaging disc 61 is mounted. As shown in Figure 6, the gear teeth upon the end plate 34 are carried by a ring 123. The end plate 34 is also shown as having an arm 124 which projects into the energy storing spring 33 eccentric to the axis of the shaft 122. This arm 124 carries a radially extending pin 125 that engages a spiral groove 126 formed in a collar-like member 127 that is keyed upon the shaft 122. The purpose of the pin 125 and the spiral groove 126 is to produce a definite axial movement of the end plate 34 with respect to the end plate 32 as the energy storing spring 33 operates to give up energy by a rotation of the shaft 122, or to take up energy by a relative rotation of the end plate 34 with respect to the end plate 32. This axial movement of the end plate 34 provides a means, as will hereinafter appear, for effecting a control of the circuit for the spring winding motor 37 and also rendering the circuit breaker controlling mechanism 14, and particularly the reclosing control elements thereof, operative in the event that the energy storing spring 33 reaches a predetermined unwound condition. This figure of the drawings also shows the movable stop 39 which cooperates with the end plate 34 as mounted in a recess 128 formed upon the supporting plate 38. The movable stop 39 is held in engaging relation with the outer face of the end plate 34 by means of a compression spring 129 so that as the end plate 34 moves in and out, the stop 39 will move accordingly. Cooperating with the stop 39, the outer surface of the end plate 34 is provided with stepped or inclined surfaces which provide radially extending ridges 130 that are adapted to engage the movable stop 39 and thus prevent rotation of the end plate 34 in all but its spring winding direction of rotation. In addition to the above function, the radially extending ridges 130 upon the end plate 34 provide a ratchet-like surface with which the plate engaging member 40 is adapted to cooperate. As here shown, the plate engaging member 40 is carried by a member 131 journaled upon the supporting plate 38 concentric to the shaft 122 and is held in pressed engagement with the end plate 34 by means of a compression spring 132. With this arrangement it will be understood that when the manually operable lever 41 is oscillated through arcs of substantially 90°, the plate engaging member 40 will successively engage the radial ridges 130 upon the end plate 34 and produce a ratchet-like means for manually winding the energy storing spring 33. A further and important feature to be noted in connection with Figure 6 of the drawings is the provision of a series of four equally spaced pins 133 upon the spring driven gear 31. These pins 133 serve, as will hereinafter appear, to set the automatic circuit breaker reclosing elements of the controlling mechanism 14 in operation. As shown more particularly in Figure 7 of the drawings, the supporting plate 38 has a portion 75

134 which carries a shaft 135 upon which the idler gear 35 is journaled in cooperating relation with the pinion 36 upon the electric motor 37 and the gear teeth upon the ring 123 carried by the end plate 34. Another feature which is illustrated in this latter figure of the drawings is the provision of a vertically disposed lever 136 which is pivotally mounted intermediate its ends upon spaced ears 137 formed upon the inside of the supporting plate 38. This lever 136 has an extension 138 at its upper end that is adapted to engage an operating button 139 upon a normally closed circuit controlling switch 140 and effect an opening of the motor circuit when the spring 33 reaches a wound condition and the end plate 34 approaches its outermost position with respect to the end plate 32. The switch controlling movement of the lever 136 is produced by a roller 141 carried thereby and biased into engagement with the surface upon the ring 123 by means of a spring 142, as is more clearly shown in Figure 1 of the drawings. At its lower end the lever 136 also carries one end of a push rod 143 that is adapted to cooperate with the slideable member 90 of the control mechanism 14 in a manner to be described in connection with Figure 14 of the drawings.

Before passing on to the remaining figures of the drawings for a description of the reclosing time delay elements of the control mechanism 14, attention is called to the fact that the spring winding motor 37 is not of the conventional type. As previously suggested, this motor is of a non-reversible type. The particular motor construction here partially illustrated comprises two opposed armatures or magnetic cores 144 which are attracted toward each other by electromagnetic forces set up in a field coil 145 that is energized from an alternating current source of supply. The armatures 144 are secured upon the ends of a U-shaped spring steel support 146 in such a manner that when the field coil 145 is energized, the armatures 144 will vibrate with respect to each other. Associated with the armatures 144 and mounted upon each of the arms of the spring steel support 146 there is a one-way acting clutch means 147 that provides a driving connection between the vibrating armatures 144 and a disc 148 carried by a shaft 149 upon which the pinion 36 is mounted. A motor of the type here illustrated, but of different construction, forms the subject matter of a copending application Serial No. 301,781, of Joseph S. Thompson, filed October 28, 1939, and entitled Electromagnetic motor, which application became Patent No. 2,274,875 on March 3, 1942. It may be added that the use of a motor of this type in combination with an energy storing spring operating in the manner here disclosed is considered novel and is to be made the subject matter of a separate application for patent.

Reference is now made to Figures 8, 9, 10 and 11 for a detailed description of the manner in which the reclosure timing mechanism 93 is set in operation upon an opening of the circuit breaker by the energy storing spring 33. As illustrated in Figure 8 of the drawings, the shaft 95 that carries the sector 92 upon which the lug 91 is formed also carries an enclosed gear sector 150 that is geared to a suitable timing means or escapement mechanism 151. The gear sector 150 is also shown as biased into an upper and inoperative position by means of a compression spring 152 which is capable of exerting a sufficient torque upon the shaft 95 to operate the escape-

ment mechanism 151 and also carry the link forming device 87 upwardly to collapse the toggle links 84 and 85 and thus move the abutment forming member 110 of the reclosing latch 84 out of latching relation with the abutment 82 upon the disc 81, as previously suggested. Upon referring particularly to Figures 9 and 10 of the drawings, it will be seen that the operating shaft 85 of the reclosing timing mechanism 83 extends through to the rear of this device where it supports an extending tongue or lever 153 which, under normal operating conditions, is disposed in the path of the projecting pins 133 upon the gear 81 that drives the disc 81 upon which the circuit breaker operating crank 28 is mounted. In these figures of the drawings a portion of the gear 81 is shown for the purpose of indicating the relative location of the pins 133 thereupon with respect to the tongue or lever 153. With this arrangement it will be seen that as the gear 81 rotates sufficiently to carry the eccentric crank 28 through a one-half revolution to open the circuit breaker contacts, one of the pins 133 thereupon will engage the tongue or lever 153 upon the timer shaft 85 and rotate this shaft through a predetermined arc and compress the timer operating spring 152. At the end of this operation the tongue or lever 153 will be released and the shaft 85 will be returned to its original position by the spring 152. During this return movement of the shaft 85, the sector 82 with its projecting lug 91 will also return to its initial position at a predetermined speed as determined by the timing escapement mechanism 151, and when the projecting lug engages the link forming device 87, it will trip the toggle links 84 and 85 and permit the energy storing spring 83 to reclose the circuit breaker contacts. At this point it should also be noted that the back of the timing mechanism 83 is provided with an arcuate ridge 154 that is adapted to hold the tongue or lever 153 outwardly and in engagement with a cooperating pin 133 throughout its engagement therewith. This ridge 154, however, terminates at its upper end at a point where the tongue or lever 153 is free to move inwardly and out of the path of the pins 133. In order to hold the end of the tongue or lever 153 outwardly and in the path of the pins 133, which is its normal operating position, the slideable member 164 previously referred to as controlled by the lever arm 71, is here shown as provided with a wedge forming end 155 which, when in the position illustrated, will serve to hold the end of the tongue or lever 153 in its outer operative position. The slideable member 164 is here shown as having a slot 156 through which a screw 157 passes to secure it slidably upon the back of the panel-like support 16. As is shown in detail in Figure 11, the tongue or lever 153 is pivotally mounted upon a pin 158 carried by the shaft 85 and is biased into an inoperative position, as shown by dot and dash lines, by means of a compression spring 159. Before passing on to the remaining figures of the drawings for a more detailed description of the reclosing time controlling mechanism, reference is again made to Figure 9 for the purpose of calling attention to the manner in which an interlocking circuit for the push button controlled electromagnets 82 and 100 are provided for. As here illustrated, the panel-like support 16 has two sets of spring contacts, designated by the numerals 160 and 161, which constitute what are commonly referred to as A and B switches. These A and B

switches, as is well understood in the art, are respectively closed and open when the circuit breaker contacts are closed, and when the circuit breaker contacts are open, these switches 5 160 and 161 are respectively open and closed. For the purpose of operating these A and B switches 160 and 161, the shaft 28 upon which the disc 81 is mounted, carries an eccentric cam 162 that is engaged by a pivotally mounted 10 forked member 163 which carries an insulating switch engaging member 164 that is adapted to alternately open and/or close the interlocking switches 160 and 161 as the circuit breaker contacts are operated respectively between their 15 closed and open circuit positions. In the arrangement here shown the A switch contacts 160 will be connected in the push button circuit of the electromagnetic coil 82, and the B switch contacts 161 will be similarly connected in the 20 circuit of the electromagnetic coil 100, shown in Figure 3 of the drawings.

Reference is now made to Figures 12, 13, 14 and 15 of the drawings, wherein further details of the reclosing timer mechanism 83 and the 25 manner in which it is associated with the reclosing latch mechanism 84 is illustrated. As shown in these figures of the drawings, it will be noted that in addition to the sector 82 with its projecting lug 91, the shaft 85 also carries an additional 30 tripping member 165 that carries a projecting lug 166 which is also adapted to engage the link forming device 87 to effect a collapsing of the toggle formed by the links 84 and 85. The lug 166 on the tripping member 165 is normally positioned slightly in advance of the lug 91 upon the sector 82, but, as is more clearly illustrated in 35 Figure 13, this tripping member 165 is biased for a relative tripping movement independently of and with respect to the sector 82 by means of a 40 spring 167. The spring 167 is positioned between a downwardly extending arm 168 carried by the tripping member 165 and a latching lever 169 which is pivotally mounted upon a shaft 170 carried by the sector 82. The latching lever 169 has a 45 projecting end 171 which is adapted to engage a shoulder 172 upon the tripping member 165 when the parts are in their normal position, and at a point between its pivotal axis and the projecting end 171 this latching lever 169 has a shoulder 173 which is adapted to be engaged by 50 the shoulder 172 formed upon the tripping member 165, as is illustrated in this figure of the drawings. At its other end the latching lever 169 is adapted to engage a stationary stop 174 as the sector 82, upon which it is mounted, is rotated 55 clockwise upon an opening of the circuit breaker contacts. When the parts are in this position, it will be seen that the projecting lug 166 upon the tripping member 165 has moved upwardly a distance sufficient to engage the link forming device 87 and effect a collapse of the toggle formed 60 by the links 84 and 85. When the latching lever 169 is brought into engagement with the stationary stop 174 and the sector 82 continues in its 65 clockwise rotation, the spring 167 will be placed under an increased tension and as soon as the projecting end 171 upon the latching lever 169 disengages the shoulder 172 upon the tripping member 165, this latter member will be rotated 70 in a counter-clockwise direction under the influence of the spring 167 and independently of the sector 82 and engage the link forming device 87. This will produce a substantially instantaneous 75 reclosing of the circuit breaker contacts independently of the timing mechanism 83 which

continues to operate to effect a subsequent time delayed reclosing of the circuit breaker contacts. It will be understood that if normal conditions have been established upon the line during the interval between the initial opening and this instantaneous reclosing, the lug 91 upon the sector 92 will be ineffective, as the link forming device 87 will be held out of its path. On the other hand, if the abnormal condition still exists after this instantaneous reclosing, the reclosing timing mechanism 93 will continue to operate until the lug 91 upon its sector 92 comes into engagement with the link forming device 87 to again trip the reclosing latch 84 and effect a subsequent delayed reclosing of the circuit breaker contacts. At this point the timing mechanism 93 will continue to operate and, if the circuit breaker remains in its closed position, the upward movement of its sector 92 will continue until the extending arm 168 upon the tripping member 165 engages the stop 174. Then, as the sector 92 continues to move upwardly, it will carry the shaft 170 with the latching lever 169 upwardly and thus store energy in the spring 167. This relative movement between the tripping member 165 and the sector 92 will also carry the projecting end 177 of the latching lever 169 into latched engagement with the shoulder 172 upon the tripping member 165 and the timing mechanism 93 will then be reset to effect an instantaneous and, if necessary, subsequently time delayed reclosing of the circuit breaker. In this connection it will be understood that where a number of subsequent time delayed reclosings are necessitated, the sector 92 upon the reclosing timing mechanism 93 will not have time between these operations to rotate counter-clockwise a distance sufficient to effect a resetting of the instantaneous tripping member 165 with respect to the sector 92 and, as a result, the lug 166 upon the tripping lever 165 will not be brought down far enough to become operative during these subsequent delayed reclosings, but will remain displaced upwardly from the lug 91 upon the sector 92, as shown in Figures 13 and 14 of the drawings. As illustrated in Figure 12, it will be noted that the member 89 is provided with an outwardly extending tongue portion 175 that projects into the path of a pin 176 carried by the link forming device 87 and to which the spring 88 is connected. This tongue 175 upon the member 89 is so disposed in the path of the pin 176 that when the link forming device 87 is moved upwardly by an operation of the reclosing timer mechanism 93, the pin 176 carried thereby will engage the inner edge of the tongue 175 and cause the link forming device 87 to be rotated clockwise. This will cause the link forming device 87 to become disengaged from the projection 91 or the projection 166 carried respectively by the timed sector 92 and the instantaneous tripping member 165 when the toggle formed by the links 84 and 85 has been collapsed sufficiently to move the abutment forming member 110 with its roller 114 out of latching relation with the abutment 62 upon the disc 61. Upon comparing the position of the link forming device 87, as shown in Figures 12 and 14 of the drawings, it will be noted that in the former figure the spring 88, which is carried by the member 89, is disposed above the pivotal axis of the link forming device 87, whereas when the member 89 is rotated into the position illustrated in the latter figure of the drawings by an upward movement of the slidable member 90, the spring 88 will be positioned at the other side of the pivotal

point of the link forming device 87. From this it will be seen that when the member 89 has been rotated into this latter position, the projecting tongue 175 and the spring 88 will operate to bias the link forming device 87 outwardly and into a position where the lugs 91 and 166, respectively carried by the sector 92 and the instantaneous tripping member 165, may pass thereby and thus be rendered ineffective to produce a reclosing of the circuit breaker when the energy storing spring 88 has unwound sufficiently to produce the required displacement of the end plate 34 which, as previously suggested, operates through the push rod 143 to control the slidable member 90. It will be noted, upon referring to Figure 15 of the drawings, that the link forming device 87 carries a horizontally extending rod 177 that is of a length sufficient to span the paths of movement of the projecting lugs 91 and 166 carried respectively by the sector 92 and the tripping member 165 and the projecting end of the manually operable tripping lever arm 94. It will also be seen that the pin 176 upon the link forming device 87 which carries the spring 88 extends outwardly through the plane of the member 89 so that in its upward movement it will be brought into engagement with the projecting tongue portion 175 previously referred to as formed upon the member 89.

For an understanding of the operation of our invention, reference should now be made to Figures 1, 2 and 3 of the drawings for a description of its operation under manual and so-called remote push button control. For this purpose it will be assumed that the energy storing spring 88 is fully wound and that the disc 61 is held in the position shown in Figure 3 by the latch mechanism 63, and that as a consequence the contact bridging member 25 of the circuit breaker is in its circuit closed position. Now, should it be desired to open the circuit breaker manually, the operator need only pull down on the push-pull rod 71. This will rock the lever arm 71 upon its pivotal support 72 and bring the pin 73 at the end thereof into engagement with the boss 14 carried by the link 48 and impart an upward movement thereto. This upward movement of the link 48 will collapse the toggle formed by the links 65 and 66 upon the latch mechanism 63 and move the abutment 110 with its roller 114 out of engagement with the abutment 62 carried by the disc 61 and thus permit the energy storing spring 88 to rotate the disc 61 through an angle of 180° where the abutment 62 will engage the roller 114 carried by the abutment forming member 110 of the latch mechanism 64. When this operation is completed, it will be seen that the pitman 27 carried by the crank arm 28 will cause the lever arm 26 upon the shaft 19 to be pulled down and thus the levers 20 upon the shaft 19 will also move downwardly so as to move the bar 22 and the contact supporting members 24 carried thereby downwardly until the contact bridging member 25 with its contacts 51 are out of circuit making engagement with the stationary contacts 53 of the circuit breaker. Now, should it be desired to close the circuit breaker manually, the operator need only push up on the push-pull rod 71 and rock the lever means 97 upwardly about its pivotal support 72. This will move the link 96 upwardly and carry the independent tripping lever arm 94 upon the reclosing timer shaft 95 into tripping relation with the link forming device 87 to collapse the toggle formed by the links 84 and 85 of the reclosing latch mechanism 64. This col-

lapsing of the toggle links 84 and 85 will move the abutment 110 with its roller 114 out of the path of the abutment 61 carried by the disc 61 and permit the energy storing spring 33 to rotate the disc 61 back into engagement with the roller 114 carried by the abutment 110 of the latch mechanism 63, as shown in Figure 3 of the drawings. In the event that the circuit breaker is provided with a remotely located push button control station, it will be understood that the electromagnetic coils 82 and 100 will be connected in a circuit with the opening and closing push buttons so that they may be energized from a suitable source of electric power as desired to open or close the main contacts of the circuit breaker. As shown in Figure 3, if the electromagnetic coil 82 is energized, the armature 81 associated therewith will be pulled up and as a result the lever arm 71 will be rotated about its pivotal axis 72 and thus effect an opening operation of the circuit breaker, as outlined above. Conversely, if the electromagnetic coil 100 is energized, this will cause the armature 101 to move up and rotate the lever means 87 and thus lift the independent lever arm 84 of the reclosing timer mechanism 93 into engagement with the link forming device 87 and trip the toggle links 84 and 85 to release the disc 61. This will permit the energy storing spring 33 to open the contacts of the circuit breaker, as has also been described hereinabove in connection with the manual operation of the circuit breaker. During both of the above opening operations, which involve an upward movement of the lever arm 71, it will be seen that the downwardly and rearwardly disposed arm 103 carried thereby will move and carry the slidable member 104 to the right, as viewed in Figure 3 of the drawings, and to the left, as viewed in Figures 9 and 10 of the drawings. This movement on the slidable member 104 will carry the wedge forming member 105 at the end thereof out from under the lever 103 carried by the shaft 85 of the reclosing timer mechanism 93 and permit the lever 103 to move out of the path of the pins 133 carried by the gear 81 as the energy storing spring 33 operates to effect the opening operation of the circuit breaker. As a result of this, in the event of a normal or push button operation of the control mechanism 14, the reclosing timer mechanism 93 will not be set in operation and, therefore, the disc 61 will be stopped and held by the reclosing latch mechanism 64 with the circuit breaker in its open circuit position.

A complete automatic operation of our improved circuit breaker through a series of opening and reclosing operations, such as would occur in the event of a sustained overload or fault upon the power line in which the circuit breaker is connected, will now be described. Under these conditions, as in the description of the manual and push button controlled operation, it will be assumed that the energy storing spring 33 is in its fully wound condition with the contact bridging member 25 in its closed circuit position and that the elements of the control mechanism 14 are in the positions illustrated in Figure 3 of the drawings. At this point, since it is being assumed that the energy storing spring 33 is fully wound, it should be pointed out that in Figure 1 of the drawings the energy storing spring 33 is shown in its unwound condition in order to illustrate the manner in which the lever arm 103 operates to control the motor circuit and through the rod 143 to render the reclosing timer mechanism 93 inop-

erative when the energy storing spring 33 reaches this unwound condition.

Under the assumed conditions, if an overload or fault occurs upon the power circuit of the circuit breaker, one or more of the trip coils 42, depending upon the phases of the power line affected, will become energized and exert a downwardly pulling force upon its associated insulated rod 44 and cause the trip shaft 45 to be rotated through an arc sufficient to carry the crank arm 47 upwardly, as viewed in Figure 3. This rotation of the shaft 45 will cause the end of the crank arm 47 to exert a pull on the timer link 49. This will move the end of the crank arm 47 in the slot 67 of the link 48 with a delayed time action, as determined by the timer mechanism 69. As soon as the end of the crank arm 47 reaches the end of the slot 67 in the link 48, further rotation of the crank arm 47 will cause the link 48 to collapse the toggle formed by the links 85 and 86 of the opening latch 63 and release the disc 61. As soon as the disc 61 is thus released, the energy storing spring 33 will operate through its driving gear 81 and the pinion 38 to rotate the disc 61 and bring the abutment 62 carried thereby into latched relation with the roller 114 carried by the abutment 110 of the reclosing latch mechanism 64. At the same time, as the gear 81 rotates to impart this movement to the disc 61, one of the pins 133 carried thereby will engage the lever 103 which is supported upon the timer shaft 85 at the rear of the timer mechanism 93. As this pin 133 engages this lever 103 it will rotate the shaft 85 and carry the sector 92 and the instantaneous trip member 86 downwardly against the action of the reclosing timer compression spring 152. After this operation, the pin 133 will become disengaged with the lever 103 and as a result the sector 92 of the timer mechanism will be free to return slowly under the influence of the compression spring 152 at a speed determined by the escapement mechanism 151. However, upon this initial downward movement of the sector 92, the latch lever 169 carried thereby will engage the stop 174 and be moved sufficiently to carry the projecting end 171 carried thereby out of engagement with the shoulder 172 upon the instantaneous trip member 165. This will permit an immediate return of the instantaneous trip member 165 through an arc sufficient to engage the link forming device 87, as shown in Figure 13, and effect an immediate release of the disc 61 and consequently provide what might be described as an instantaneous reclosing of the circuit breaker. Now, should the overload or fault be of a continuing nature, as assumed, one of the trip coils 42 will again respond upon a closing of the circuit breaker contacts and as a result the lever arm 47 will again be moved upwardly to effect a second opening of the circuit breaker contacts in the manner above described for the first opening of the circuit breaker. When the circuit breaker contacts are thus opened a second time, another one of the pins 133 will engage the lever 103 carried by the shaft 85 at the back of the reclosing timer mechanism 93 and again move the sector 92 downwardly against the action of the compression spring 152. During this interval, however, the latch 169 carried by the sector 92 will not have become reset and, therefore, the projecting end 166 thereof will not be moved down far enough to again engage the link forming device 87 and, therefore, there will be no instantaneous tripping of

the toggle links 84 and 85, as was the case in the previous reclosing operation. In this instance, however, the sector 92 upon the reclosing timer mechanism 83 will be released and, as in the first instance, again move upwardly under the influence of the compression spring 152 until the projecting lug 91 upon the sector 92 comes into tripping engagement with the link forming device 87 to effect a tripping of the toggle formed by the links 84 and 85. In this latter reclosing operation, it will be seen that the reclosing timer mechanism 83 with its sector 92 will operate to trip the toggle mechanism formed by the links 84 and 85 after a predetermined time delay, as determined by the escapement 151. From this it will be seen that up to this point the circuit breaker contacts have been operated through one immediate reclosing operation and one delayed reclosing operation. Now, should the overload or fault still prevail upon the circuit in which the circuit breaker is connected, the last described reclosing operation will be again repeated. During the instantaneous and the two time delayed reclosing operations thus described, it will be understood that the energy storing spring 83 will give up its energy at a rate greater than the energy can be restored thereto by means of the motor 87 and, therefore, the end plate 84 carried thereby will move inwardly into the position shown in Figure 1 of the drawings, where the lever 136 carried by the end plate 84 will be permitted to move under the influence of the spring 142 and thus impart a movement to the push rod 143 which will cause the slidale member 88 to be moved upwardly in a diagonal path into the position illustrated in Figure 14 of the drawings, where the link forming device 87 will be held out of interfering relation with the projecting lugs 91 and 156 carried respectively by the sector 92 and the instantaneous trip member 155 of the reclosing timer mechanism 83. Upon the last opening operation of the circuit breaker, it will be seen that since the link forming device 87 has been rendered inoperative by this displacement of the end plate 84 and the consequent movement of the slidale member 88, the toggle formed by the links 84 and 85 will remain extended and as a result the disc 81 will be finally stopped by the latch mechanism 64 in a position where the contact bridging member 25 of the circuit breaker will be held out of circuit making engagement with the line terminals of the circuit breaker. During the above operation it will also be understood that as the lever 136 is permitted to rotate under the influence of the spring 142, the extension 138 at the upper end thereof will be moved out of engagement with the operating button 139 of the normally closed motor circuit controlling switch 148 and as a result the motor 87 will continue to operate to rewind the energy storing spring 83. After the circuit breaker has been latched in either its open or closed circuit position, the motor 87 will continue to operate to rewind the energy storing spring 83 until the end plate 84 carried thereby has moved outwardly a sufficient distance to cause the lever 136 to move and bring its extending end 138 into circuit opening engagement with the button 139 of the normally closed switch 148.

While we have, for the sake of clearness and in order to disclose our invention so that the same can be readily understood, described and illustrated specific devices and arrangements,

we desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described our invention, what we claim and desire to secure by Letters Patent is:

1. In an automatic reclosing circuit breaker of the character described, the combination of circuit controlling means, an energy storing spring for operating said circuit controlling means through a series of circuit opening and circuit reclosing operations, a latch means for holding said circuit controlling means in its closed circuit position, a second latch means for holding said circuit controlling means in its open circuit position, means responsive to load conditions upon the circuit in which said circuit controlling means is connected adapted to render said first latch inoperative and permit said energy storing spring to move said circuit controlling means into its circuit open position, and means responsive to said energy storing spring adapted upon an initial opening operation of said circuit controlling means to render said second latch inoperative when said circuit controlling means reaches its circuit open position and permit an immediate reclosing of said circuit controlling means by said energy storing spring.
2. In an automatic reclosing circuit breaker of the character described, the combination of circuit controlling means adapted to be connected in a power circuit, an energy storing spring adapted to operate said circuit controlling means through a series of circuit opening and circuit reclosing operations, a latch means for holding said circuit controlling means in its closed circuit position, a second latch means for holding said circuit controlling means in its open circuit position, means responsive to load conditions upon the power circuit in which said circuit controlling means is connected adapted to render said first latch inoperative and permit said energy storing spring to move said circuit controlling means into its circuit open position, means responsive to said energy storing spring adapted upon an initial opening operation of said circuit controlling means to render said second latch inoperative when said circuit controlling means reaches its circuit open position and permit an immediate reclosing of said circuit controlling means by said energy storing spring, and means for rendering said last means inoperative in the event of an immediate circuit reopening operation of said circuit controlling means by said energy storing spring.
3. In an automatic reclosing circuit breaker of the character described, the combination of circuit controlling means, an energy storing spring for operating said circuit controlling means through a series of circuit opening and circuit reclosing operations, a latch means for holding said circuit controlling means in its closed circuit position, a second latch means for holding said circuit controlling means in its open circuit position, means responsive to a fault or overload condition upon the power circuit in which said circuit controlling means is connected adapted to render said first latch inoperative and permit said energy storing spring

to move said circuit controlling means into its circuit open position, a latch tripping means responsive to said energy storing spring upon an initial opening operation of said circuit controlling means adapted to render said second latch inoperative when said circuit controlling means has reached its full circuit open position, whereby said circuit controlling means will be immediately operated by said energy storing spring to reclose the circuit controlled thereby, and means for rendering said latch tripping means inoperative after said initial opening and reclosing operation in the event of a sustained fault or overload condition upon the power circuit in which the circuit controlling means is connected.

4. In an automatic reclosing circuit breaker of the character described, the combination of circuit controlling means, an energy storing spring adapted to operate said circuit controlling means through a series of circuit opening and circuit reclosing operations, a latch means for holding said circuit controlling means in its closed circuit position, a second latch means for holding said circuit controlling means in its open circuit position, means responsive to an overload condition upon the power circuit in which said circuit controlling means is connected adapted to render said first latch inoperative and permit said energy storing spring to move said circuit controlling means into its circuit open position, a latch tripping means responsive to said energy storing spring upon an initial opening operation of said circuit controlling means adapted to render said second latch inoperative when said circuit controlling means has reached its circuit open position, whereby said circuit controlling means will be immediately operated by said energy storing spring to reclose the circuit controlled thereby, means for rendering said latch tripping means inoperative after said initial circuit reclosing operation in the event of a sustained fault or overload condition upon the power circuit in which the circuit controlling means is connected, and a delayed action latch tripping means responsive to said energy storing spring for rendering said second latch inoperative after a predetermined time interval following any circuit opening operation of said circuit controlling means by said energy storing spring immediately following the initial reclosing operation thereof in response to said latch tripping means.

5. In an automatic reclosing circuit breaker of the character described, the combination of circuit controlling means adapted to open and close a power circuit, an energy storing spring for operating said circuit controlling means through a series of circuit opening and circuit reclosing operations, a latch means for holding said circuit controlling means in its closed circuit position, a second latch means for holding said circuit controlling means in its open circuit position, means responsive to load conditions upon the circuit in which said circuit controlling means is connected adapted to render said first latch inoperative and permit said energy storing spring to move said circuit controlling means into its circuit open position, a timing mechanism adapted to be set in operation by said energy storing spring during each opening operation of said circuit controlling means, means controlled by said timing mechanism adapted in the event of a sustained fault or overload upon the power circuit to render said second latch inoperative

10 after a predetermined interval of lapsed time to permit a reclosing of said circuit controlling means by said energy storing spring, and means associated with said timing mechanism adapted upon an initial circuit opening operation of said circuit controlling means in response to the means responsive to load conditions upon the power circuit to render said second latch inoperative independently of said timing mechanism and permit an immediate reclosing of said circuit controlling means by said energy storing spring.

6. In an automatic reclosing circuit breaker of the character described, the combination of circuit controlling means adapted to open and close 15 a power circuit, an energy storing spring for operating said circuit controlling means through a series of circuit opening and circuit reclosing operations, a latch means for holding said circuit controlling means in its closed circuit position, 20 a second latch means for holding said circuit controlling means in its open circuit position, means responsive to load conditions upon the circuit in which said circuit controlling means is connected adapted to render said first latch inoperative and permit said energy storing spring to move said circuit controlling means into its circuit open position, a timing mechanism adapted to be set in operation by said energy storing spring upon each opening operation of said circuit controlling means, means associated with said timing mechanism adapted upon an initial circuit opening operation of said circuit controlling means in any one series of circuit opening and circuit closing operations to render said second latch inoperative 25 independently of said timing mechanism and permit an immediate reclosing of said circuit controlling means by said energy storing spring, other means controlled by said timing mechanism adapted upon each subsequent opening operation 30 of the circuit controlling means resulting from a sustained fault or overload upon the power circuit to render said second latch inoperative after predetermined intervals of lapsed time to effect a plurality of subsequent reclosing operations of 35 said circuit controlling means by said energy storing spring, and means responsive to an unwound condition of said energy storing spring for rendering said timing mechanism inoperative upon said second latched means after a predetermined 40 number of reclosing operations of said circuit controlling means.

7. In an automatic reclosing circuit breaker of the character described, the combination of circuit controlling contacts adapted to be moved out of and into engagement with each other to 45 respectively open and close a load circuit, an energy storing spring, means operated by said energy storing spring for moving said circuit controlling contacts through a series of circuit opening and circuit reclosing operations, a latching means for holding said means against operation by said energy storing spring when said contacts are in their circuit closed position, electromagnetic means responsive to load conditions 50 upon the circuit controlled by said contacts, mechanical means operated by said electromagnetic means adapted to render said latching means inoperative and permit an operation of said energy storing spring and movement of said circuit controlling contacts into an open circuit position in the event of an overload or fault upon the circuit controlled thereby, and a mechanical timing device associated with said mechanical means and operating independently of 55 current conditions upon the circuit for intro-

ducing a predetermined time delay between the operation of said electromagnetic means in response to an overload or fault and the release of said shaft by said latching means.

8. In an automatic reclosing circuit breaker of the character described, the combination of circuit controlling contacts adapted to be moved out of and into engagement with each other to respectively open and close a power transmission circuit, an energy storing spring, a shaft adapted to be rotated by said energy storing spring, means operated by rotation of said shaft for moving said circuit controlling contacts through a series of circuit opening and circuit reclosing operations, a latching means for holding said shaft against rotation by said energy storing spring when said contacts are in their circuit closed position, an overload tripping device responsive to load conditions upon the circuit through said contacts, means operated mechanically by said overload tripping device adapted to render said latching means inoperative and permit a movement of said circuit controlling contacts into a circuit open position by said energy storing spring in the event of an overload or fault upon the power transmission circuit, and a mechanical action delaying device associated with said last means for retarding its operation by said overload tripping device and introducing a predetermined time interval between the actuation of said overload tripping device and the release of said shaft by said latching means.

9. In an automatic reclosing circuit breaker of the character described, the combination of circuit controlling contacts adapted to be moved out of and into engagement with each other to respectively open and close a power transmission circuit, an energy storing spring, a shaft adapted to be rotated by said energy storing spring, means operated by rotation of said shaft for moving said circuit controlling contacts through a series of circuit opening and circuit reclosing operations, a latching means for holding said shaft against rotation by said energy storing spring when said contacts are in their circuit closed position, electromagnetic means responsive to load conditions upon the circuit through said contacts adapted to render said latching means inoperative and permit a movement of said circuit controlling contacts into an open circuit position by rotation of said shaft in the event of an overload or fault upon the power transmission circuit, a mechanical lost motion link connection between said last means and said latching means, and an action delaying device associated with said lost motion link connection for introducing a predetermined time interval between the occurrence of an overload or fault upon the power transmission circuit and the release of said shaft by said latching means.

10. In an automatic reclosing circuit breaker of the character described, the combination of circuit controlling contacts adapted to be moved out of and into engagement with each other to respectively open and close a power transmission circuit, an energy storing spring, a shaft adapted to be rotated by said energy storing spring, means operated by rotation of said shaft for moving said controlling contacts through a series of circuit opening and circuit reclosing operations, a latching means for holding said shaft against rotation by said energy storing spring when said contacts are in their closed circuit position, means responsive to load conditions upon the power transmission circuit adapted to

render said latching means inoperative and permit a movement of said circuit controlling contacts into an open circuit position by rotation of said shaft in the event of an overload or fault upon the power transmission circuit, a second latching means for stopping rotation of said shaft when said contacts reach their circuit open position, a timing mechanism adapted to be set in operation by said energy storing spring upon each opening operation of said circuit controlling contacts, means controlled by said timing mechanism adapted in the event of a sustained fault or overload upon the power circuit to render said second latch inoperative after a predetermined interval of lapsed time following each opening operation of said circuit controlling contacts to effect a plurality of subsequent reclosing operations of said circuit controlling contacts by said energy storing spring, and means responsive to an unwound condition of said energy storing spring for rendering said timing mechanism inoperative to control said second latching means after a predetermined number of reclosing operations of said circuit controlling means.

11. In an automatic reclosing circuit breaker of the character described, the combination of circuit controlling contacts adapted to be moved out of and into engagement with each other to respectively open and close a power transmission circuit, an energy storing spring, a shaft adapted to be rotated by said energy storing spring, means operated by rotation of said shaft for moving said circuit controlling contacts through a series of circuit opening and circuit reclosing operations, means normally holding said shaft against rotation by said energy storing spring when said contacts are in their closed circuit position, means responsive to load conditions upon the power transmission circuit adapted to render said normally holding means inoperative in the event of an overload or fault upon the power transmission circuit, a latching mechanism adapted to stop rotation of said shaft by said energy storing spring when said circuit controlling contacts are in their circuit open position, and means set in operation by said energy storing spring upon an initial operation thereof to rotate said shaft and move said circuit controlling contacts into their open circuit position adapted to render said latching mechanism inoperative, whereby said energy storing spring will operate to rotate said shaft and effect an immediate circuit reclosing movement of said circuit controlling contacts.

12. In an automatic reclosing circuit breaker of the character described, the combination of circuit controlling contacts adapted to be moved out of and into engagement with each other to respectively open and close a power transmission circuit, an energy storing spring, a shaft adapted to be rotated by said energy storing spring, means operated by rotation of said shaft for moving said circuit controlling contacts through a series of circuit opening and circuit reclosing operations, means normally holding said shaft against rotation by said energy storing spring when said contacts are in their closed circuit position, means responsive to load conditions upon the power transmission circuit adapted to render said normally holding means inoperative in the event of an overload or fault upon the power transmission circuit, a latching mechanism adapted to stop rotation of said shaft by said energy storing spring when said circuit controlling contacts are in their circuit open po-

sition, means set in operation by said energy storing spring upon an initial operation thereof to rotate said shaft and move said circuit controlling contacts into their open circuit position arranged and adapted to render said latching mechanism inoperative, whereby said energy storing spring will operate to rotate said shaft and effect an immediate circuit reclosing movement of said circuit controlling contacts, and a timing means associated with said last means adapted upon an immediate subsequent circuit opening movement of said circuit controlling contacts to render said means operative to release said latching mechanism after a predetermined interval of lapsed time, whereby in the event of a continuing overload or fault upon the power transmission circuit said circuit controlling contacts will be operated through a series of at least two reclosing operations the first one of which will occur immediately following the first circuit opening operation of said circuit controlling contacts and the second of which will occur after a predetermined time interval following a second circuit opening movement of said circuit controlling contacts.

13. In an automatic reclosing circuit breaker of the character described, the combination of circuit controlling means, a driving shaft for operating said circuit controlling means through a series of circuit opening and circuit reclosing operations, a torsional energy storing spring secured at one end to said driving shaft and arranged concentrically thereto, an end plate slidably and rotatably mounted upon said driving shaft and to which the other end of said torsional energy storing spring is connected, means for holding said end plate against rotation upon said driving shaft when said spring is wound to store energy therein, means carried by said driving shaft and cooperating with said end plate for imparting a definite axial movement to said end plate as said driving shaft is rotated by said energy storing spring, and means responsive to the axial movement of said end plate adapted to render said circuit controlling means inoperative upon a predetermined axial movement of said end plate as said energy storing spring unwinds to impart rotation to said driving shaft.

14. In an automatic reclosing circuit breaker of the character described, the combination of circuit controlling means, a driving shaft for operating said circuit controlling means through a series of circuit opening and circuit reclosing operations, a torsional energy storing spring attached at one end to said driving shaft and arranged concentrically thereto, an end plate slidably and rotatably mounted upon said driving shaft and to which the other end of said torsional energy storing spring is connected, means for holding said end plate against rotation upon said driving shaft when said spring is wound to store energy therein, a spiral guide means carried by said driving shaft, a guide engaging means carried by said end plate for imparting a definite axial movement to said end plate as said driving shaft is rotated by said energy storing spring, and means cooperating with said end plate adapted to render said circuit controlling means inoperative in the event of a predetermined axial displacement of said end plate upon said shaft as said energy storing spring unwinds to rotate said driving shaft.

15. In an automatic reclosing circuit breaker of the character described, the combination of circuit controlling means, a driving shaft for op-

erating said circuit controlling means through a series of circuit opening and circuit reclosing operations, a torsional energy storing spring attached at one end to said driving shaft and arranged concentrically thereto, an end plate slidably and rotatably mounted upon said driving shaft and to which the other end of said torsional energy storing spring is connected, an electric motor for rotating said end plate about said driving shaft to wind and store energy in said energy storing spring, means carried by said driving shaft and cooperating with said end plate for imparting a definite axial movement to said end plate as it is rotated relative to said driving shaft by said electric motor, an energizing circuit for said electric motor, a normally closed circuit controlling switch in said circuit for controlling the energization of said electric motor, and means responsive to the axial movement of said end plate upon said driving shaft resulting from a rotation thereof by said electric motor adapted to open said normally closed switch and disconnect the electric motor from said energizing circuit.

16. In an automatic reclosing circuit breaker of the character described, the combination of circuit controlling means, an energy storing spring for operating said circuit controlling means through a series of circuit opening and circuit reclosing operations, a latch means for holding said circuit controlling means in a closed circuit position, a second latch means for holding said circuit controlling means in its open circuit position, means responsive to said energy storing spring adapted upon an opening operation of said circuit controlling means to render said second latch inoperative when said circuit controlling means reaches its open circuit position and permit an immediate reclosing of said circuit controlling means by said energy storing spring, manually operable means for rendering said first latch means inoperative and permitting said energy storing spring to move said circuit controlling means into its circuit open position, and means controlled by said manual means adapted to render the means responsive to said energy storing spring inoperative in the event of a manually controlled opening operation of said circuit controlling means.

17. In an automatic reclosing circuit breaker of the character described, the combination of circuit controlling means adapted to open and close a power circuit, an energy storing spring for operating said circuit controlling means through a series of circuit opening and circuit reclosing operations, a latch means for holding said circuit controlling means in its closed circuit position, a second latch means for holding said circuit controlling means in its open circuit position, means responsive to load conditions upon the circuit in which said circuit controlling means is connected adapted to render said first latch inoperative and permit said energy storing spring to move said circuit controlling means into its circuit open position, a timing means for delaying the operation of said first latch means by said means responsive to load conditions, a second timing means adapted to be set in operation by said energy storing spring during each opening operation of said circuit controlling means, means controlled by said second timing means adapted in the event of a sustained fault or overload upon the power circuit to render said second latch inoperative after a predetermined interval of lapsed time to permit a reclos-

ing of said circuit controlling means by said energy storing spring, and means associated with said second timing means adapted upon an initial circuit opening operation of said circuit controlling means in response to the means responsive to load conditions upon the power circuit to render said second latch inoperative independently of said second timing means, whereby said circuit controlling means will operate to provide a delayed opening, an immediate reclosing and a series of delayed openings and reclosings of the controlled circuit in the event of a sustained fault or overload thereupon.

18. In an automatic reclosing circuit breaker having relatively movable contacts adapted to control a load circuit, an operating shaft for controlling the relative movements for said contacts,
